HEATING OF HYDROCARBON FLUIDS

Filed Oct. 1, 1949

UNITED STATES PATENT OFFICE

2,667,449

HEATING OF HYDROCARBON FLUIDS

Valentine Mekler, Jackson Heights, N. Y., assignor to The Lummus Company, New York, N. Y., a corporation of Delaware

Application October 1, 1949, Serial No. 119,076

11 Claims. (Cl. 196—73)

1

This invention relates to improvements in the art of heating hydrocarbon fluids predominantly by radiant heat applied to banks of tubing through which a charge of the fluid is passed within a furnace chamber. More particularly, the invention is concerned with improved performance of pyrolysis of light hydrocarbon gases to obtain desired olefins as, for example, the cracking of ethane or propane to obtain ethylene. A temperature of around 1400° F. is required for such cracking and, in applying the required heat to the tubing which contains the charge, much care must be taken to obtain a proper rate of heat input along the course of the charge, prevent objectionable coke deposit within the tubing and also avoid damage to the tubing by overheating. U. S. Patent No. 2,456,786 of Ludwig Kniel et al. and U. S. Patent No. 2,456,787 of Ludwig Kniel disclose methods and apparatus devised particularly for performance of such cracking. The present application is directed to improvements over the disclosures of said patents.

An important object of the invention is to provide for more flexible control of heat input to the course of the charge so that a desired temperature curve may be obtained more readily.

A further object of the invention is to provide for adequate heating of a cracking portion of the course while protecting other portions of the course from overheating and damage to the tubing.

A still further object is to provide a heating apparatus embodying an improved combination and arrangement of tube banks, burners and shield means devised to afford the desired flexible control of heat input and also protect the tubing from overheating.

Further objects and advantages will appear from the following description and the accompanying drawings.

In the drawings:

Fig. 1 is a vertical transverse section of a furnace embodying the invention;

Fig. 2 is a horizontal section, on a reduced scale, taken on the line 2—2 of Fig. 1, a portion of the furnace being broken away and some details of the wall structure being omitted; and

Fig. 3 is a diagrammatic view showing a modified arrangement of the tubing.

According to the invention, the charge to be heated is passed in separate streams through a pair of tube banks located along opposite side walls of a furnace chamber. Then, the fluid is passed from said side banks through a bank of tubes lying within a plane intermediate said side banks. Combustion is conducted within outer regions of the chamber adjacent the side banks and within inner regions at opposite sides of said intermediate bank to preheat the charge within the side banks predominantly by radiant heat and further heat the charge within the intermediate bank, predominantly by radiant heat, to conver-

2

sion temperature. Overheating of the side banks is prevented by the shielding effect of walls which separate said inner and outer combustion regions. These walls protect the side banks from the heat of combustion within said inner regions which raises the charge within the intermediate bank to conversion temperature. Provision is also made for conducting combustion within additional regions of the furnace chamber located at 16 opposite sides of the said intermediate plane and outwardly of said shield walls and said inner and outer combustion regions for additional radiant heat input to tubing within said plane. In one form of the invention, the tubing in said plane 15 includes, in addition to the cracking bank, a preliminary heating bank through which the charge is passed en route to the side banks. This preliminary bank is heated by radiant heat from the combustion within said additional regions. Combustion gases are passed from the inner and outer 20 regions into said additional regions and escape through an outlet from the latter.

Referring to Figs. 1 and 2, a furnace chamber 1 is formed by a floor or hearth 2, opposite side walls 3 and vertical ends walls 4. Lower portions 3a of the side walls 3 are vertical and upper portions 3b thereof converge upwardly to an outlet flue 5 located in a vertical central plane of the furnace. All of said walls are constructed of blocks or slabs 6 of refractory material sheathed with heat insulation 7. Columns 8 support the furnace chamber elevated from the ground or from a foundation.

Within the furnace chamber a pair of outer tube banks 9 are supported in vertical planes adjacent the vertical portions 3a of the respective side walls. A pair of intermediate tube banks 10 and 11 are supported, one above the other, within the vertical central plane of the chamber. Each 35 of the four tube banks comprises a single vertical row of spaced horizontal tubes all in a vertical plane and serially connected by return bends for flow of the charge in a serpentine course through all of the tubes of the bank in succession. A charge delivery pipe 12 leads to the uppermost tube of the upper central bank 10 and two transfer pipes 13 lead from the lowermost tube of the bank 10 to the uppermost tubes of the side banks 9, respectively. From the lowermost tubes of the side banks respectively, transfer tubes 14 lead 40 to the uppermost tube of the lower central bank 11. A discharge pipe 15 leads from the lowermost tube of bank 11. Since the tubes of the bank 10 are required to deliver the charge to both of the side banks 9, and the tubes of the bank 11 are required to receive the charge from both of the side banks, the tubes of the central banks are of 45 greater diameter than the tubes of the side banks.

The side wall banks are coextensive and at the same level within the furnace chamber and they are horizontally opposed to the lower central bank 11. Heat shields in the form of a pair of

bridge walls 16 of refractory material extend upwardly from the hearth 2, at opposite sides of the bank 11. These walls are located approximately midway between the bank 11 and the side banks 9 and they extend above the topmost level of the latter. As shown, the central bank 11 may extend above the level of the upper edges of the bridge walls. Beneath the banks 9 and 11 there are also narrow horizontal refractory shield walls 17. The walls 16 and the walls 17 extend from end to end of the furnace chamber.

At the bottom of the furnace chamber there are four rows of burners arranged to fire upwardly through ports in the hearth 2. The burners 18 of two of said rows are arranged respectively, to conduct combustion within the regions between the bridge walls 16 and the side banks 9. The burners 19 of the other two rows are arranged to conduct combustion within the regions at opposite sides of the bank 11 and between same and the walls 16. At opposite sides of the upper central bank 10 there are two horizontal rows of burners 20 arranged to fire laterally inwardly through flared ports 21 in the side walls of the furnace chamber. Thereby, combustion may be conducted within regions at opposite sides of the bank 10. The burners 20 are mounted, as at 22, for vertical angular adjustment and they are spaced substantially above the level of the upper edges of the bridge walls 16. The burners 18, 19 and 20 are provided with valves 23 for combustion control. These valves may be either individual to the burners or individual to the different rows of burners so that combustion within the different regions may be controlled independently.

In the operation of the furnace just described, the charge, which may be a hydrocarbon gas such as ethane or propane, for example, is introduced through the delivery pipe 12 and passed downwardly through the bank 10 which constitutes a preliminary heating bank. Within this bank the charge which may be relatively cold upon introduction is preheated by radiant heat from the combustion conducted by the side burners 20 and from combustion gases rising past the opposite sides of the bank from all of the combustion regions of the chamber to the outlet 5 which leads to a stack, not shown. Heat is also reradiated to opposite sides of the bank 10 by the converging walls 3b. At the lower end of the bank 10 the charge is split and passed through the transfer pipes 13 and downwardly through the side banks 9. Within the side banks, the charge is further preheated, predominantly by radiant heat, through combustion conducted by the burners 18 and by reradiation from the walls 16. The walls 17 at the bottom of the banks 9 serve as shields to prevent overheating of the lower tubes of the banks. The charge, preheated within the tube banks 10 and 9, is passed through the transfer pipes 14 and downwardly through the bank 11 which constitutes a conversion or cracking bank. This bank is heated predominantly by radiant heat from combustion conducted by the burners 19 and by heat reradiated from the walls 16. Within all of the tube banks the charge is passed counter-current to the rising combustion gases and toward the hottest portion of the furnace. The conversion products are discharged through the pipe 15. The wall 17 underlying the bank 11 shields the lower tubing of the bank and prevents overheating thereof.

Combustion adequate for effecting conversion

of the charge within the bank 11 may be had without risk of overheating and damaging of the tubing of the preheating banks owing to the provision of the walls 16 which separate the preheating regions of combustion from the conversion regions of combustion and shield the tubes of the banks 9. That renders it possible to employ less expensive tubing in the preheating banks than in the conversion banks whose tubes require an alloy affording high heat resistance. The separation of the combustion regions and the arrangement of the tube banks and the independently controllable burners also provide a high degree of flexibility in the control of heat input to the charge in its course through the tubing and facilitate the obtaining of a desired heat curve. The adjustability of the burners 20 renders it possible to direct them toward either the bank 10 or the upper portion of the conversion bank 11 for selective heat input.

In the form of the invention shown in Fig. 3 the furnace walls, the side tube banks 9, the bridge walls 16 and the burners, here indicated by arrows, are all in an arrangement similar to that shown in Fig. 1. The bank 10, however, is omitted and the central conversion bank, here designated 11a, is extended upwardly to take the place of the omitted bank. The charge is introduced in separate streams, through pipes 12a, to the respective side wall banks 9, and transfer pipes 14a lead from the lowermost tubes of said banks to the uppermost tube of the central bank 11a. The charge in its downward passage through the bank 11a is heated predominantly by radiant heat from combustion conducted by the burners 20 and 19 in succession and is also heated by reradiation from the walls 3b and from combustion gases rising past the bank to the outlet 5. As in the first form of the invention, provision is made for prevention of overheating of the preheating tubing, independent control of combustion within the different regions and substantially uniform distribution of heat around the circumference of the tubes of the conversion bank. Such distribution of heat around the cross section of the individual tubes prevents cold spots upon which coke will accumulate.

It is, of course, to be understood that the present disclosure of my invention is merely illustrative and in nowise limiting and that the invention comprehends such modifications as will come within the scope of the claims.

I claim:

1. A heater for hydrocarbon fluid, comprising a furnace chamber, a pair of banks of preheating tubes within said chamber and adjacent opposite walls thereof, a bank of advanced heating tubes extending between said preheating banks in a plane intermediate the latter, burners disposed to conduct combustion within regions between said bank of advanced heating tubes and said preheating banks and in direct exposure to the respective banks to heat all of said banks predominantly by radiant heat, a bank of preliminary heating tubes within the furnace chamber and in said intermediate plane and beyond said preheating tubes, burners disposed to conduct combustion within regions at opposite sides of said preliminary heating bank and in direct exposure thereto for radiant heating of same, each of said four banks having an inlet and an outlet for the fluid, conduits connecting the outlet of said preliminary heating bank to the inlets of said preheating banks to pass the fluid thereto, and conduits connecting the outlets of the preheating banks to the inlet of said advanced heat-

ing bank therebetween to pass the fluid thereto. 2. The heater claimed in claim 1 wherein the said burners for conducting combustion at opposite sides of the said preliminary heating bank are directed inwardly toward the said plane and are mounted for angular adjustment with reference to the plane.

3. A heater for hydrocarbon fluid, comprising a furnace chamber, a pair of banks of preheating tubes within said chamber and adjacent the side walls thereof, a bank of advanced heating tubes extending between and beyond said preheating banks in a plane intermediate the latter, each of said banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said dividing walls serving to shield the preheating banks from the heating effects of the combustion within said inner regions, and burners disposed to conduct combustion within regions of the chamber at opposite sides of said intermediate plane and adjacent the portion of the bank of advanced heating tubes which extends beyond the preheating banks, for radiant heating of said bank portion, said last-mentioned burners being directed toward said plane and mounted for angular adjustment with reference to said plane.

4. A heater for hydrocarbon fluid, comprising a furnace chamber, a pair of banks of preheating tubes within said chamber and adjacent opposite walls thereof, a bank of advanced heating tubes extending between said preheating banks in a vertical plane intermediate the latter, each of said three banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said dividing walls serving to shield the preheating banks from the heating effect of the combustion within said inner regions, a bank of preliminary heating tubes within the chamber and located within said plane, above the bank of advanced heating tubes and beyond said inner combustion regions and having an inlet and an outlet for said fluid, conduits connecting the outlet of said bank with the inlets of both of said preheater banks for delivery of the fluid thereto, and burners disposed to conduct combustion within regions of the chamber at opposite sides of the bank of preliminary heating tubes to heat same by radiant heat, the said inner and outer regions opening into said regions at opposite sides of the bank of preliminary heating tubes and the

chamber having gas outlet means opening from the last-mentioned regions.

5. The method of heating a hydrocarbon fluid, comprising passing said fluid in a confined stream along a preliminary heating course, conducting the fluid from said course in a pair of confined streams along a pair of transversely opposed spaced preheating courses, conducting the fluid from both of said courses in a single confined stream along an advanced heating course extending in a plane between said preheating courses, said preliminary heating course being in a position offset in said plane from said advanced heating course, conducting combustion within outer regions between said advanced course and said preheating courses and in direct exposure to the latter respectively to heat same predominantly by radiant heat, conducting combustion within inner regions between said preheating courses and said advanced course and in direct exposure to opposite sides of the latter to further heat the fluid in the advanced course predominantly by radiant heat, shielding the preheating courses from the heating effect of the combustion within said inner regions, conducting additional combustion within regions at opposite sides of said preliminary heating course and in direct exposure thereto for radiant heating thereof, and conducting combustion gases from all of the said combustion steps through the last-mentioned regions.

6. The method of heating a hydrocarbon fluid, comprising passing said fluid in a pair of confined streams along a pair of transversely opposed spaced preheating courses, conducting the fluid from both of said courses in a single confined stream along an advanced heating course extending in a plane between said preheating courses, conducting combustion within outer regions between said advanced heating course and said preheating courses and in direct exposure to the latter respectively to heat same predominantly by radiant heat, conducting combustion within inner regions between said preheating courses and said advanced course and in direct exposure to opposite sides of the latter to further heat the fluid in the advanced course predominantly by radiant heat, shielding the preheating courses from the heating effect of the combustion within said inner regions, and conducting additional combustion within regions spaced from said inner and outer regions and at opposite sides of and in exposure to said advanced heating course for radiant heating thereof.

7. A heater for hydrocarbon fluid, comprising a furnace chamber, a pair of banks of preheating tubes within said chamber and adjacent the opposite walls thereof, a bank of advanced heating tubes extending between said preheating banks in a plane intermediate the latter, each of said three banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said

dividing walls serving to shield the preheating banks from the heating effect of the combustion within said inner regions, and burner means disposed to conduct combustion within regions of said chamber at opposite sides of said intermediate plane and spaced along said plane from said inner and outer regions for additional radiant heating of the bank of advanced heating tubes.

8. A heater for hydrocarbon fluid, comprising a furnace chamber, a pair of banks of preheating tubes within said chamber and adjacent opposite walls thereof, a bank of advanced heating tubes extending between said preheating banks in a plane intermediate the latter, each of said three banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said dividing walls serving to shield the preheating banks from the heating effect of the combustion within said inner regions, the bank of advanced heating tubes extending beyond said preheating banks, and burners disposed to conduct combustion within regions of said chamber at opposite sides of said intermediate plane and adjacent the portion of the bank of advanced heating tubes which extends beyond the preheating banks, for radiant heating of said bank portion.

9. A heater for hydrocarbon fluid, comprising a furnace chamber, a pair of banks of preheating tubes within said chamber and adjacent opposite walls thereof, a bank of advanced heating tubes extending between said preheating banks in a plane intermediate the latter, each of said three banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said dividing walls serving to shield the preheating banks from the heating effect of the combustion within said inner regions, a bank of preliminary heating tubes within the furnace chamber, located within said intermediate plane and beyond said inner combustion regions and having an inlet and an outlet for said fluid, conduits connecting the outlet of said bank with the inlets of both of said preheating banks for delivery of the fluid thereto, and burner means disposed to conduct combustion within regions of the chamber at opposite sides of said bank of preliminary heating tubes to heat same by radiant heat, the said inner and outer regions opening into said regions at opposite sides of the bank of preliminary heating

tubes and the chamber having gas outlet means opening from the last-mentioned regions.

10. A heater for hydrocarbon fluid, comprising a furnace chamber, a pair of banks of preheating tubes within said chamber and adjacent opposite walls thereof, a bank of advanced heating tubes extending between said preheating banks in a plane intermediate the latter, each of said three banks having an inlet and an outlet for the fluid, conduits leading from the outlets of the preheating banks to the inlet of said bank of advanced heating tubes to pass therethrough the fluid from both of said preheating banks, walls between the bank of advanced heating tubes and the preheating banks and dividing the chamber into outer combustion regions at the inner side of the preheating banks and inner combustion regions at opposite sides of the bank of advanced heating tubes and separated thereby, burners disposed to conduct combustion within all of said regions in direct exposure to the respective banks to control independently the combustion within said inner and outer regions, said dividing walls serving to shield the preheating banks from the heating effect of the combustion within said inner regions, a bank of preliminary heating tubes within the furnace chamber, located within said intermediate plane and beyond said inner combustion regions and having an inlet and outlet for said fluid, conduits connecting the outlet of said bank to the inlets of both of the preheating banks for delivery of the fluid thereto, and burner means disposed to conduct combustion within regions of the chamber at opposite sides of preliminary tubes to heat same by radiant heat.

11. The method of heating a hydrocarbon fluid to a conversion temperature, comprising passing said fluid in a pair of confined streams substantially vertically along a pair of spaced transversely opposed serpentine preheating courses, conducting the fluid from both of said courses in a single confined stream downwardly from a point above the level of said preheating courses substantially vertically along a serpentine advanced heating course extending between said preheating courses, conducting combustion within outer regions between said advanced heating course and said preheating courses and in direct exposure to the latter respectively to heat same predominantly by radiant heat, conducting combustion within inner regions between said preheating courses and said advanced heating course and in direct and substantially equal exposure to opposite sides of the latter course to heat the stream therein substantially uniformly around its cross section predominantly by radiant heat, shielding said preheating courses from the heating effect of the combustion within said inner regions, and conducting additional combustion at opposite sides of said advanced heating course and in direct exposure thereto within regions spaced above the level of said inner and outer regions to radiantly heat the upper portion of the advanced heating course.
